UNITED STATES PATENT OFFICE.

ROBERT STICKDORN, OF MUNICH, GERMANY.

FLUSH DEVICE FOR WATER-CLOSETS.

Application filed February 27, 1926, Serial No. 91,126, and in Germany March 7, 1925.

My invention relates to the known flush devices for water closets of the type comprising an air reservoir containing no water when the apparatus is at rest. As soon as 5 the flush is to pass through the closet, the reservoir is connected with the water pipe by means of the hand actuation of a control device forming a piston. When the reservoir is filled up to a certain point with the water 10 which has entered it after compressing the air, it is connected with the flush pipe through the pressure in the air reservoir which brings the piston back into its rest position, where it sets the opening of the 15 flush pipe free and closes the feed aperture.

In the known flush devices of this type the movement of the piston into the position where the reservoir is allowed to be fed with water, is produced generally by the action 20 of the hand on a rod secured to the piston. This control arrangement requires that a comparatively great resistance should be overcome so that in some cases, weak persons or children experience some difficulty in 25 making the apparatus work. On the other hand, as soon as the pressure in the air reservoir has reached the value necessary for the flush to be produced, the flush passes through the closet with such a rush that there is a 30 somewhat great water hammer effect produced in the feed pipe.

According to my invention, these drawbacks are completely removed by providing for the movement of the piston by means of 35 a screw having a great pitch, the said pitch being such that by rotating the screw by a fraction of a revolution only the piston is brought into its feed position, the movement of the piston being however much easier 40 than when the piston rod has to be pulled. On the other hand the screw provided with a great pitch which when the piston has been moved, must be brought back through the pressure of the water produces a certain 45 braking action and thereby prevents too speedy a flush. Besides, this new arrangement also allows the flush to be produced by a mere action of the hand before the pressure in the air reservoir has reached the 50 value normally required for passing from the feed to the flush position, whereby the flush can be produced with a lesser amount of fluid than in the normal case.

A form of execution of my invention is 55 shown by way of example on appended drawings whereof.

Fig. 1 shows the air reservoir seen from behind with its flush device.

Fig. 2 is a vertical section at an enlarged scale, through the middle axis of the flush 60 device seen in its rest position.

Fig. 3 is a similar section with the flush device in its feed position.

Fig. 4 is a cross section along the line 65 IV—IV of Fig. 2.

The air reservoir 1 is V-shaped and is connected at its lowest point which is in its middle with the flush pipe through the blow off connection.

The flush valve passes through the whole 70 of the air reservoir above which a control crank 13 is secured to the valve rod projecting above the reservoir. The connection placed behind the reservoir for receiving the water feed pipe is shown at 4. Inside 75 the air reservoir is the casing 5 of the valve. About the middle of its height, this casing is connected with the water feed pipe through the said connection 4 passing into the rear of the reservoir. At its lower part inside the 80 air reservoir, the casing shows a crown of apertures 26 wherethrough it is in connection with the inside of the air reservoir. The casing 5 comprises in the first place three parts 5^a, 5^b, 5^c, having different diameters; the part 5^a is separated from the part 5^b by a watertight sleeve 6: the part 5^b is separated from the part 5^c by a watertight sleeve 7. In a similar manner a watertight sleeve 8 is disposed at the lower end of the 90 part 5^c of the casing between the casing and the blow-off 2. Between the sleeves 6 and 7 is disposed in the casing a cylindrical grid 9 which is to break the water jet passing into the casing through the connection 4 so as to 95 prevent the pressure of this jet from acting only on one side of the piston disposed in the casing. At the same time the grid muffles the noise of the water entering the casing.

The controlling piston which is hollow 100 throughout its height shows steps along its length. Its top part 10^a has a diameter somewhat greater than its lower part 10^b. Between these two parts is a narrow part 10^c and the part 10^b ends at its lower part 105 with a still narrower part 10^d. The part 10^a moves always in front of the sleeve 6 whereas the part 10^b is made watertight by the sleeve 7 when the piston is raised (Fig. 2) and by the sleeve 8 when it is lowered 110 (Fig. 3).

The casing of the control valve is closed

by a threaded plug 11 projecting outside the air reservoir. This plug shows a hole along its axis and acts as a bearing for the hollow rod 12 to the top of which is secured the 5 crank 13. The hub of the crank is hollow and shows at its lower side apertures 14. Inside this hollow hub of the crank, the hollow rod also shows a crown of holes 15. The air can thus pass into the hollow stem and as 10 latter is open at its lower end, passes into the hollow piston 10 which is open throughout its length whereby the water is completely emptied.

The rod 12 shows at its lower part 12^a 15 which is separated from the top part passing through the bearing-plug 11 by the flange 16 a long-pitched thread. A corresponding nut is provided by a thread borne by the top of the higher part 10^a of the 20 piston. It is of advantage to choose the thread so as to allow a half revolution of the crank 13 to be sufficient to bring the piston from its higher position shown on Fig. 2 to its lower position shown on Fig. 3.

Of course, to allow the piston 10 to move 25 along its axis when the threaded rod is made to rotate, it must be secured in a manner which prevents it from rotating. In view of this, a flange 17 is placed at the top of the piston. It shows two notches 18 placed at the two opposite ends of a diameter and these notches engage longitudinal projections 20 secured inside the casing. The projections 20 are integral with the sleeve 19 30 which through the pressure of the threaded plug 11, serves to keep the sleeve 6 in place and thereby the grid 9 and the sleeve 7. In the case where the sleeve 6 is not absolutely watertight and in view of preventing the 35 flush of water from passing above this sleeve and entering inside the casing above the said sleeve, the part 10^a shows inside the part containing the threaded nut and which is reinforced internally a crown of longitudinal 40 channels 21 through which the flush of water when it reaches the top end of the piston can flow inside the piston and from there into the flush pipe.

The working of the apparatus is as follows:

In Fig. 2 it is supposed that after the flush device has been actuated, the piston 10 is still in its higher position where the air reservoir is connected with the flush pipe 45 through the holes 26 and the sleeve 8 which in this position is not in contact with the part 10^b. The piston is kept in this position by the pressure of the water which exists in the chamber comprised between the sleeves 6 and 50 7, this chamber being connected constantly through the connection 4 with the feed pipe. Under these conditions, the actuating force is the excess pressure exerted on the larger top part 10^a.

If a flush is desired the crank 13 is ro-

tated by 180° and is moved towards the front of the figure. The position shown in Fig. 3 is thus obtained. The piston is brought then to its lower position as shown on Fig. 3 under the action of the thread 12^a. The 70 sleeve 7 is brought in front of the narrow part 10^c and the sleeve 8 is in watertight contact with the part 10^b so that the water is allowed to pass into the air reservoir through the chamber disposed between the 75 sleeves 6 and 7, the narrow part 10^c and the holes 26. The crank 13 can then be brought back into its original position (Fig. 2) after passing in front of the plane of the figure, when water has been allowed to enter the 80 reservoir during the desired time. The piston 10 is then raised to its position in Fig. 2 under the action of the thread 12^a. As the sleeve 7 bears in a watertight manner against the part 10^b, the water cannot continue entering the air reservoir and the provision of water already contained in the reservoir can flow into the flush pipe through the holes 26 and the sleeve 28 which no longer provides for watertightness. If it is desired to obtain 85 for the flush the normal quantity of water, there is nothing more to do once the piston is brought into the position shown on Fig. 3. The reason is that when a given water pressure is obtained in the reservoir 90 this water pressure makes the piston 10 rise because of the shape of this piston divided in parts of unequal diameter, so that the passage from feed to flush position is automatic. During this automatic raising of the 95 piston, the rod 12 with its crank 13 is brought through the action of the thread 12^a into the position shown on Fig. 2 so that after the air reservoir is emptied, all the parts of the 100 apparatus are ready to provide for a new 105 flush. Of course the threaded rod which is to be rotated affords a certain resistance to the rising of the controlling piston whereby a sudden stopping in the entrance of the 110 water in the piston casing and consequently the production of water hammer effects is prevented.

If requested, the threaded rod could be mounted loose on the piston so as to prevent its sliding along the direction of the axis and the closing plug could be provided with the nut thread. The device intended for preventing the piston from rotating could then be dispensed with. The form of execution described is however preferable.

What I claim is:

A device for controlling the flush in flush devices for water closets comprising an air reservoir adapted to communicate with the flush-pipe, a casing in said reservoir, a vertical differential piston the largest part of which is uppermost adapted to move freely in the casing and to close the communication of the air chamber on one hand with the casing and on the other with the flush pipe

when it is respectively in its higher and lower position, a water supply pipe opening in the casing in front of the piston, threads provided on the piston, a threaded spindle cooperating with the said threads and adapted to rotate without moving longitudinally, a crank controlling said piston, and means

for preventing the rotation of the piston whereby it is caused to move vertically under the action of the crank.

10

In witness whereof I have hereunto set my hand.

ROBERT STICKDORN.
